SIGNORS TO INGERSOLL-RAND COMPANY, OF JERSEY CITY, NEW JERSEY, A COR-
PORATION OF NEW JERSEY

DRILL-FEEDING DEVICE

Application filed July 17, 1928. Serial No. 283,429.

This invention relates to rock drills, but more particularly to a feeding device for fluid actuated rock drills of the drifter type.

The objects of the invention are to maintain a suitable pressure on the rock drill for feeding it towards the work in accordance with the penetration of the drill steel into the material being drilled and to facilitate the operation of withdrawing the drifter from the work.

Other objects will be in part obvious and in part pointed out hereinafter.

In the drawings illustrating a practical application of the invention and in which similar reference characters refer to similar parts,

Figure 1 is a longitudinal elevation, partly in section, of a rock drill and its shell having the invention applied thereto;

20 Figure 2 is a plan view, partly in section,

Figure 3 is a plan view in section of the throttle valve for the feeding cylinder,

25 Figures 4, 5 and 6 are transverse views taken on the lines 4—4, 5—5 and 6—6 looking in the direction indicated by the arrows and showing the throttle valve in various positions for controlling the feeding device, and

30 Figure 7 is a transverse view, in section taken on the line 7—7 of Figure 1 looking in the direction indicated by the arrows.

Referring to the drawings, A designates generally a rock drill comprising a percussive cylinder B on which may be formed the usual guides (not shown) which cooperate with guideways C of a shell D whereby the rock drill A is supported. On the front end of the cylinder A is a front head E into which extends a working implement F for cutting holes G into material intended to be drilled, 35 such as the rock H. A back head J forms a closure for the rearward end of the cylinder B and said back head J and the front head E may be secured to the cylinder by means of spring pressed bolts K.

40 On the side of the cylinder B is mounted a valve chest L in which may be disposed a suitable distributing valve (not shown) for effecting the distribution of pressure fluid to the cylinder B. Such pressure fluid is conveyed 45 from a suitable source of supply to the valve

chest L by means of a connection or hose O and passes through a passage P in the valve chest controlled by a throttle valve, only the lever Q of which is shown.

The shell D may be of the well known type 55 having a conical extension E' for cooperation with suitable clamping means, such as are usually provided on a drill column or quarry bar for clamping the drilling mechanism thereto.

60 In accordance with the present invention, means are provided for advancing the rock drill A towards the work, such as the rock H, and for retracting it therefrom through the medium of pressure fluid after the hole has been drilled. To this end the cylinder A is provided with a lug R which, in the construction shown, is of substantially the same length as the cylinder A and extends into the shell D. The lug R is provided with a recess S into which extends a feeding cylinder T of a suitable length, depending upon the distance which it is desired to cause the rock drill to travel relatively to the work.

65 The feeding cylinder T may consist of a 70 tube having open ends and on the rearward end of said feeding cylinder is disposed a cap U forming a head therefor. Preferably, the cap U is provided with holes V on opposite sides to receive tie rods or bolts W which project with their opposite ends through lugs X on the lug R for securing the cap U and thus also the cylinder T securely to the lug R. A shoulder Y is formed in the recess S to act as a seat for the inner end of the cylinder T.

75 The recess S is formed in the rearward end of the lug R, thus leaving a wall Z at the front end of the recess and a hole b is formed in the wall to accommodate a piston rod c 80 which extends into the feeding cylinder and is connected to a piston d in the feeding cylinder T.

85 The opposite end of the rod c is in this instance fixedly secured to a plate e bolted to the front end of the shell D, the end f of the rod c being threaded to receive a nut g. Preferably the outer end of the bore b is enlarged somewhat to receive suitable packing means h which surround the rod c for pre- 150

venting leakage of pressure fluid from the recess *S* and a packing gland *j* is threaded into the outer end of the bore *d* for compressing the packing *h*.

6 Suitable means are provided for selectively exposing the ends of the piston *b* to pressure fluid to actuate the drill *A* longitudinally of the shell *D*, both for feeding the drill steel *F* into the rock *H* and for 10 retracting it therefrom. The means provided for this purpose in the present instance consist of a throttle valve *k* disposed in a throttle valve chamber *o* formed in a boss *p* at the front end of the cylinder *B*. Suitable 15 passages *q* and *r* in the cylinder lead from the throttle valve chamber *o* to the rearward and front ends respectively of the feeding cylinder *T*. From the rearward end of the passage *q* extends a tube *s* seated with 20 one end in the cap *U* for conveying pressure fluid from the passage *q* to the rearward end of the feeding cylinder *T*.

The throttle valve *k* in this instance has a passage *t* to register with the passages *r* and 25 *q* and said passage *t* is in constant communication with the passage *P* in the valve chest *L* through a passage *u* formed in the cylinder *A* and the valve chest *L*.

In order to enable pressure fluid to be exhausted from the ends of the feeding cylinder *T*, the throttle valve *k* is provided with an external groove *v* which may simultaneously register with either of the passages *r* or *q* and with an exhaust port *w* in the boss 30 *p*. The throttle valve *k* is provided with the usual lever *x* for manually rotating the throttle valve.

In the operation of the device, the throttle valve *k* may be rotated to a position to admit 40 pressure fluid through the passage *r* into the front end of the feeding cylinder as illustrated in Figure 5. Pressure fluid thus admitted into the front end of the feeding cylinder will force the rock drill in the direction of the rock *H*. The percussive element of the drill may then be set in operation and the 45 pressure fluid in the front end of the feeding cylinder will exert a pressure sufficient to advance the rock drill towards the work in accordance with the penetration of the drill steel *F* into the rock.

50 After the rock drill has reached the forward most limit of its travel the throttle valve *k* may be rotated to the position shown in Figure 6 to carry the passage *t* into registry with the passage *q*. The groove *v* will then be in a position to establish communication between the passage *r* and the exhaust port *w*. In this position of the throttle valve, the 55 pressure fluid previously used for feeding the rock drill to the work will be exhausted to the atmosphere and pressure fluid will be admitted through the passage *q* and the tube *s* into the rearward end of the feeding cylinder. Such pressure fluid will cause the rock

drill to be quickly retracted from the work. After another drill steel has been substituted for one previously used, the throttle valve *k* 70 may be again reversed to supply pressure fluid to the front end of the feeding cylinder to feed the rock drill in a forwardly direction.

75 After a drilling operation has been completed and it is desired to transport the drilling mechanism from one drilling site to another, the rock drill *A* may be fed in a forwardly direction until the lug *R* lies adjacent the front end of the shell *D*. In this position substantially the entire feeding cylinder *T* will lie within the shell *D*. The throttle valve *k* may then be rotated to a neutral 80 position as illustrated in Figure 4 to establish communication between both ends of the feeding cylinder and the atmosphere through the various passages and ports leading from the throttle valve chamber *o* to the feeding 85 cylinder.

We claim:

1. In a drill feeding device, the combination of a rock drill having a percussive cylinder and a shell for the rock drill, a lug on the cylinder having a recess, a feeding cylinder extending with one end into the recess and fixedly secured to the lug, a wall in the lug forming a head for one end of the feeding cylinder and having a bore, a piston in the feeding cylinder, a rod for the piston secured to the front end of shell and extending through the bore, said rod lying wholly within the shell, and means for controlling the supply of pressure fluid in the ends of the feeding cylinder to actuate the rock drill longitudinally of the shell.

2. In a drill feeding device, the combination of a rock drill having a percussive cylinder and a shell for the rock drill, a lug on the cylinder having a recess, a feeding cylinder extending with one end into the recess and fixedly secured to the lug, a wall in the lug forming a head for one end of the feeding cylinder and having a bore, a piston in the feeding cylinder, a rod for the piston secured to the front end of the shell and extending through the bore, said rod lying wholly within the shell, a throttle valve on the forward end of the percussive cylinder, and passages leading from the throttle valve to the ends of the feeding cylinder for conveying pressure fluid to and from the feeding cylinder for actuating the rock drill in the shell.

3. In a drill feeding device, the combination of a rock drill having a percussive cylinder and a shell for the rock drill, a lug on the cylinder having a recess, a feeding cylinder extending with one end into the recess and fixedly secured to the lug, a wall in the lug forming a head for one end of the feeding cylinder and having a bore, a piston in the feeding cylinder, a rod for the piston secured to the front end of the shell and extending through the bore, said rod lying wholly 100 105 110 115 120 125 130 135 140 145 150 155 160 165 170 175 180 185 190 195 200 205 210 215 220 225 230 235 240 within the shell, a boss on the front end of the percussive cylinder having a valve chamber and an exhaust port, a passage constantly conveying pressure fluid from a source of supply to the valve chamber, inlet passages leading from the valve chamber to the ends of the feeding cylinder, and a throttle valve in the valve chamber controlling the passages and the exhaust port.

5 4. In a rock drill feeding device, the combination of a rock drill having a percussive cylinder and a shell for the rock drill having longitudinally extending guideways whereon said rock drill is slidably mounted, a lug 10 on the cylinder extending into the shell, a recess in the lug substantially parallel with the cylinder and opening at the rearward end of the lug, a feeding cylinder extending into the recess and fixedly secured to the lug, a wall 15 in the lug forming a closure for the front end of the feeding cylinder and having a bore, a piston in the feeding cylinder, a rod for the piston extending through said bore and being secured to the front end of the shell, said rod lying wholly within said shell, a boss on the percussive cylinder having a valve chamber and an exhaust port for the valve chamber, a supply passage constantly conveying pressure fluid from a source of supply to the 20 valve chamber, inlet passages leading from the valve chamber to the front and rear ends respectively of the feeding cylinder, and a valve in the valve chamber adapted to concurrently control the admission of pressure fluid 25 into one inlet passage and the exhaust of pressure fluid from the other inlet passage, said valve also being adapted to simultaneously establish communication between both inlet passages and the exhaust port.

20 In testimony whereof we have signed this specification.

WILLIAM PRELLWITZ.
RUSSELL H. WILHELM.

30 5. In a rock drill feeding device, the combination of a rock drill having a percussive cylinder and a shell for the rock drill having longitudinally extending guideways whereon said rock drill is slidably mounted, a lug on the cylinder extending into the shell, a recess 35 in the lug substantially parallel with the cylinder and opening at the rearward end of the lug, a tube extending with one end into the lug, a cap forming a closure for the other end of the tube, a pair of holes in the lug and in 40 the cap, a pair of bolts extending through the holes, nuts on the bolts for clamping the lug, the tube and the cap fixedly together, said tube and said lug forming a feeding cylinder for the rock drill and having a piston, a rod 45 secured to the piston extending through the lug and being secured to the front end of the shell, and means for admitting pressure fluid into the ends of the feeding cylinder to advance and retract the rock drill along the 50 guideways, the means for admitting pressure fluid into the rear end of the feeding cylinder including a tube extending with its ends into the percussive cylinder and the cap and clamped therebetween by the bolts and the 55 nuts.

60 6. In a rock drill feeding device, the combination of a rock drill having a percussive cylinder and a shell for the rock drill having longitudinally extending guideway whereon 65 said rock drill is slidably mounted, a lug on

the cylinder extending into the shell, a recess in the lug substantially parallel with the cylinder and opening at the rearward end of the lug, a feeding cylinder extending into the recess and fixedly secured to the lug, a wall 70 in the lug forming a closure for the front end of the feeding cylinder and having a bore, a piston in the feeding cylinder, a rod for the piston extending through said bore and being secured to the front end of the shell, said rod lying wholly within said shell, a boss on the percussive cylinder having a valve chamber and an exhaust port for the valve chamber, a supply passage constantly conveying pressure fluid from a source of supply to the 75 valve chamber, inlet passages leading from the valve chamber to the front and rear ends respectively of the feeding cylinder, and a valve in the valve chamber adapted to concurrently control the admission of pressure fluid 80 into one inlet passage and the exhaust of pressure fluid from the other inlet passage, said valve also being adapted to simultaneously establish communication between both inlet passages and the exhaust port.

85 In testimony whereof we have signed this specification.
